Primary Examiner — Eric Goodman*Assistant Examiner* — Amy Wierenga(74) *Attorney, Agent, or Firm* — Leason Ellis LLP(57) **CLAIM**

The ornamental design for a translucent mat with diamond pattern, as shown and described.

DESCRIPTION

FIG. 1 is a top plan view of the translucent mat with diamond pattern;

FIG. 2 is a side profile view thereof; the left side of the figure being representative of the top plan view of FIG. 1;

FIG. 3 is an enlarged detail view of area 3 circumscribed within or on FIG. 2; and,

FIG. 4 is an enlarged detail view of area 4 circumscribed within or on FIG. 1.

The portions of the translucent mat with diamond pattern shown in broken lines form no part of the claimed design.
